AU 292 EX

OR D 20,147

DESIGN.

—o—
A. ROSENSTEIN.

CANE OR UMBRELLA HANDLE.

No. 20,147.

Patented Sept. 9, 1890.

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,147, dated September 9, 1890.

Application filed July 31, 1890. Serial No. 360,575. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to 5 which it pertains to make and use it, reference being had to the accompanying drawing, which forms part of this specification:

My invention relates to an improvement in designs for cane, umbrella, or parasol handles; and it consists in the ornamental shape 10 and configuration of parts, whereby a novel effect is produced, as will be more fully described hereinafter.

The accompanying photographic illustration 15 represents my invention.

A represents the inner end or portion of the handle, from the outer end of which extends the branch B, which is curved around

so as to almost form a circle or ring, and which has its end to connect with or approach 25 the small projection C, which extends from this branch B. Also extending from the outer end of the part A is the slightly-curved branch D, which passes through one side of the circle or ring formed by the branch B. 30 All of the parts of this handle are provided with ribs or circles around them at about regular distances apart, so as to give the handle the appearance of bamboo which has been twisted or bent into the shape shown. 35

Having thus described my invention, I claim—

A design for a cane, parasol, or umbrella handle, substantially as herein shown and described. 40

In testimony whereof I affix my signature in presence of two witnesses.

ALBERT ROSENSTEIN.

Witnesses:

E. P. ELLIS,
ALLEN S. PATTISON.
